Primary Examiner — Catherine Ho(74) *Attorney, Agent, or Firm* — Dinsmore & Shohl LLP;
 Yongsok Choi, Esq.(57) **CLAIM**

The ornamental design for a label, as shown and described.

DESCRIPTION

The patent or application file contains at least one drawing executed in color. Copies of this patent or patent application publication with color drawing(s) will be provided by the Office upon request and payment of the necessary fee.

The FIGURE is a front view of a label, showing my new design.

The broken lines and the areas within shown in white overlay show portions of the label that form no part of the claimed design.
